UNITED STATES PATENT OFFICE.

ADDISON FOSTER PUREFOY, OF WAKE FOREST, NORTH CAROLINA.

SPRING BED-BOTTOM.

SPECIFICATION forming part of Letters Patent No. 593,781, dated November 16, 1897.

Application filed February 14, 1893. Serial No. 462,294. (No model.)

To all whom it may concern:

Be it known that I, ADDISON FOSTER PUREFOY, a citizen of the United States, residing at Wake Forest, in the county of Wake and State 5 of North Carolina, have invented certain new and useful Improvements in Spring Bed-Bottoms; and I do hereby declare the following to be a full, clear, and exact description of the invention, such as will enable others skilled 10 in the art to which it appertains to make and use the same.

This invention relates more particularly to the means for connecting brace-wires and coiled wire springs together in bed-bottoms 15 and analogous structures, as chair-seats and the like.

In the accompanying drawings, Figure I is a partial plan of a spring bed-bottom constructed in accordance with the invention. 20 Fig. II is a partial section on line *i i* of Fig. I.

In the drawings the structure at one corner only of a spring bed-bottom is represented. The parts omitted may be duplicates of those shown. It is intended to employ hour-glass 25 springs and to have a like arrangement of brace-wires on each end of the same; but any ordinary or suitable form of springs may be used, secured to any appropriate base. As shown, the springs A, which make up the 30 body of the bed-bottom, are connected with one another by the brace-wires B, running lengthwise and widthwise of the bed-bottom. The wires B are connected with the springs by means of couplings C and C', having loops 35 1 at each end and an oblique middle portion 2 and formed of a wire bent into the general form, in plan, of the figure 8. The brace-wires B running lengthwise are shown as separately secured to each of the spring-wires 40 which they intersect by means of an appropriate coupling. Each coupling extends around the spring-wire and has its ends engaged by the cross-wire which is threaded through the loops at the ends thereof.

45 In order to apply the coupling in the most firm manner, the brace-wire which passes through the loops or openings is bent about the wire or wires (whether one or more spring-wires or brace-wires, or both) which the middle portion of the coupling incloses, so that 50 there is less liability for the brace-wire to pull through.

In applying the coupling the same is bent sufficiently for the loops or openings at the ends to receive the brace-wire while the latter 55 is straight, and then the coupling and crossed wires are compressed, thereby bending the brace-wire outward around the spring-wire and forcing inward the ends of the coupling to make a smooth surface. The spring-wire 60 is confined between the middle portion 2 of the coupling and the brace-wire B. By having a separate coupling for each intersection of the brace and spring wires the springs may be set any desired distance apart. It is possible, however, and where the springs are set 65 closely together advantageous, to use one coupling to attach two adjacent springs to each other and to a brace-wire intersecting both. The advantage in this arrangement is 70 in lessening the number of joints in the bed-bottom and also the number of couplings. Although it could be applied to other brace-wires, it is shown only in connection with the 75 brace-wires running widthwise of the bed-bottom, the couplings C' being bent around the wires of adjacent springs A and having the brace-wires inserted in the loops or openings 1 of the couplings and bent outward around the inclosed spring-wires. 80

At the ends each brace-wire B is bent into a loop 3, and the end B* of each brace being lapped upon the body portion of the same brace-wire is secured thereto by means of a coupling C*, similar or identical with the 85 couplings C C'. The border-wire D is secured to the edges of the top coils of springs A by means of the looped ends 3 of the brace-wires and has each of its ends D* twisted about the spring-wire of the end spring and secured 90 thereto by an eye 4. The brace-wires are preferably flat. The spring-wires, the wires of the couplings, and the border-wires are preferably round.

I claim as my invention or discovery— 95

1. A brace-wire having at the end a loop formed by lapping said wire upon itself, in combination with a wire threaded through said loop, and a coupling having openings at the ends with the lapped portions of the brace 100 threaded through said openings and bound together by said coupling, substantially as described.

2. In combination with the coiled-wire

springs of a bed-bottom, brace-wires having the ends looped about spring-wires and being secured also to the spring-wires where they cross the same, the lapped ends of the braces being secured to the body portions thereof by bent-wire couplings having a loop at each end which receives the lapped portions of the brace-wires and an oblique body portion which crosses and confines them, and similar coup-

lings securing the brace-wires to the spring-wires at their crossings, substantially as described. 10

In testimony whereof I affix my signature in presence of two witnesses.

ADDISON FOSTER PUREFOY.
